Otto C. Vetterman,

UNITED STATES PATENT OFFICE.

OTTO C. VETTERMAN, OF PINGREE GROVE, ILLINOIS.

SELF-CLOSING STRAINER.

1,289,322.

Specification of Letters Patent. Patented Dec. 31, 1918.

Application filed May 15, 1918. Serial No. 234,727.

To all whom it may concern:

Be it known that I, OTTO C. VETTERMAN, a citizen of the United States, residing at Pingree Grove, in the county of Kane and State of Illinois, have invented certain new and useful Improvements in Self-Closing Strainers, of which the following is a specification.

This invention relates generally to strain-
ers for use in connection with milk recep-
tacles, and particularly to self-closing
strainers, having for its primary object to
generally simplify and improve the con-
struction and operation of such devices as
well as to increase their efficiency.

A further object of the invention is to
provide a strainer which is capable of being
applied to receptacles having mouths of
various sizes, and which operates automatic-
ally when the liquid within the receptacle
has reached a predetermined height to shut
off the strainer to preclude the passage of
liquid therethrough.

Further objects reside in providing a de-
vice of the character mentioned which is of
extremely simple and improved construc-
tion, which is positive in operation, which is
composed of but few simple and readily as-
sembled parts, all of the said parts being
constructed and arranged in such manner as
to minimize the opportunity for wear or
breakage, and which will prove thoroughly
practical and efficient in use.

With these objects in view, together with
others which will appear as the description
proceeds, the invention resides in the novel
formation, combination, and arrangement of
parts, all as will be described more fully
hereinafter, illustrated in the drawings, and
particularly pointed out in the claims.

In the drawings:—

Figure 1 is a vertical sectional view taken
through a strainer constructed in accord-
ance with the invention, the closing valve
for the strainer being shown in open pos-
ition,

Fig. 2 is a similar view taken at right
angles to Fig. 1, and showing the positions
the parts will assume when the valve is in
closed position, and

Fig. 3 is a top plan view of the improved
strainer.

Referring now more particularly to the
drawings, 4 indicates generally the strainer
with which the improved apparatus is used,
the said strainer comprising a body formed

of thin metal, open at both ends, and having
its side walls tapered inwardly toward the
lower end. The body or bowl 4, adjacent
the lower end thereof is constructed so as to 60
provide an inwardly projecting flange 5,
from the outer ends of which depends a ver-
tical substantially short wall 6. The lower
end of this wall is flared outwardly as at 7,
and constitutes a valve seat. A strainer 8 65
of any approved construction may be im-
serted within the tubular body 4 and rests,
as shown, upon the inwardly projecting
flange 5.

The valve used in connection with a 70
strainer body of this character for auto-
matically shutting off the flow of liquid
through the strainer when a predetermined
liquid level in the container has been
reached, is indicated at 9. This valve is 75
provided at its upper end with a reduced
neck portion 10, conforming in shape and
size to the restricted opening defined by the
depending walls 6 of the strainer body, and
the said float or valve has divergent side walls 80
11 adapted to rest against the walls 7 of the
body when the said valve is moved up-
wardly. If desired, the divergent walls 11
may be provided upon their exterior sur-
faces with suitable packing indicated at 12, 85
in order that a tight seat of the valve
against the walls 7 may be provided. The
valve member 9 is extremely light, so as to
float upon the liquid within the receptacle.

The valve 9 has extending upwardly 90
therefrom, and preferably at points diamet-
rically opposite, rods 13, which rods extend
loosely through suitable apertures in the
flange 5 and also in the flared wall 7.
These rods are connected at their upper ends 95
by a cross rod or bar 14, so that both rods
will move in unison. It will be observed
that the vertically disposed rods 13 are in-
clined outwardly above their lower extremi-
ties, so that they will rest upon the divergent 100
side walls of the body 4 when the valve 9
is in lowered or open position. The rods
thus limit the downward movement of the
valve, and it is obvious that upward pull
applied to the connecting bar 14 will cause 105
the valve to move upwardly and into en-
gagement with the seat provided by the
walls 7.

A support 15 extends across the upper
open end of the strainer body, and is secured 110
thereto by the spring clamp members 16 at
its ends. These clamp members snap over

and firmly engage beneath the annular bead at the upper end of the strainer body, so that the support is firmly held in proper position upon the said body. Hinged as at 5 17 upon the support and intermediate the ends of the latter is a lever 18. It will be observed that the lever is hollow throughout its length, and has its ends closed. A rolling weight, such as a lead ball 19, is confined 10 within the hollow lever 18, and is free to roll within the said lever in either direction, accordingly as the lever is inclined. The lower end of the lever is connected to the connecting bar 14, and it is obvious that 15 rocking movement applied to the lever will cause the float 9 to rise or lower, accordingly as the lever is rocked.

In practice, the strainer is inserted within the mouth of the receptacle to be filled, and 20 the lever 18 is rocked upwardly into the position shown in Fig. 1. This movement of the lever causes the valve 9 to be forced downwardly or in open position. Liquid poured into the strainer body will pass 25 through the strainer 8 and into the receptacle, and when the liquid level within the latter has reached the valve 9, the latter will float upwardly into close engagement with the seat 7 of the strainer. This upward 30 movement of the valve causes the rods 13 to move correspondingly, whereupon the lever 18 is tilted. Just as soon as the lever passes beyond the horizontal, the ball 19 therein will roll to the free end of the lever, causing 35 the said free end to move downwardly and to firmly bind the valve 9 in engagement with the seat 7. Any liquid which may then be in the bowl portion of the strainer cannot 40 pass into the receptacle, and will remain confined within the strainer until the valve 9 has been moved away from the seat 7. The arm 18 operates not only as a means for assisting in controlling the movements of the valve, but also as an indicating means 45 to apprise those using the strainer when the receptacle is filled.

From the above it is obvious that I have provided a strainer which is of extremely simple construction and is capable of performing its functions wholly automatically. 50 The various parts are so constructed and arranged as to enable the strainer to be read-

ily sterilized when required, and the said parts are so assembled within the body as not to interfere with the flow of liquid or to 55 affect the straining operation. Should it be desired, the vertical rods 13 may be inclosed within suitable housings within the strainer body.

While the present is a disclosure of what 60 is believed to be the preferred embodiment of the invention, it is to be understood that the invention is not limited thereto, as various changes in the minor details of construction, proportion, and arrangement of parts 65 may be resorted to if desired without departing from the spirit of the invention as defined by the appended claims.

I claim:—

1. In combination, a body having inwardly inclined downwardly extending walls, the said body being provided at its lower end with a valve seat, a valve adapted to move into or out of engagement with said seat, rods connected to said valve and extending upwardly upon the interior of said body, the upper portion of said rods being inclined outwardly equal to the degree of inclination of the said funnel walls and being adapted when the valve is at the lowest 80 point of its travel to rest upon the inclined walls of said body, and means for raising or lowering said rods.

2. In combination, a self-closing strainer comprising a body having downwardly and inwardly inclined walls adapted to be inserted in the mouth of a receptacle, a valve seat at the lower end of said body, a wall projecting into the body a short distance and around the same above said valve seat, 90 valve rods secured to the sides of said valve and extending loosely through the said wall, the said rods above the said wall being inclined outwardly at an angle equal to the inclination of the side walls of said body, 95 and means at the upper end of said body for moving said rods vertically.

In testimony whereof I affix my signature in presence of two witnesses.

OTTO C. VETTERMAN.
